WYLLYS E. DOWD, JR., OF NEW YORK, N. Y., ASSIGNOR TO FOSTER WHEELER CORPORATION, OF NEW YORK, N. Y., A CORPORATION OF NEW YORK

AIR PREHEATER

Application filed August 4, 1926. Serial No. 127,167.

The general object of the present invention is to provide improved means for utilizing available heat in the heating gases leaving a boiler furnace for preheating the air supplied to the furnace for combustion purposes. More specifically, the object of the invention is the construction of an air preheater in a novel manner, characterized by the effective manner in which the available heat in the 10 furnace gases coming to the preheater is utilized, and by the mechanical simplicity and compactness of the preheating provisions, and by the efficiency and low cost per square foot of heating surface attained.

15 The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

20 Of the drawings:

Fig. 1 is an elevation in section on the line 1—1 of Fig. 2;

Fig. 2 is a rear view of the preheater and 30 boiler arrangement partly broken away;

Fig. 3 is a side elevation with the housing broken away showing a modified preheater arrangement for another type of boiler furnace; and

35 Fig. 4 is a rear view with parts broken away for the preheater of Fig. 3.

In the drawings, Figs. 1 and 2, I have illustrated the use of my invention in connection with a blast furnace gas fired boiler A, but 40 it will be understood that the invention is adapted for use in connection with any boiler furnace, regardless of its type and the character of the fuel burned, the discharging flue gases of which may be advantageously used 45 in preheating the combustion supporting air. In the particular boiler construction shown, the heating gases leaving the combustion chamber A' follow the path shown by the arrows over water tubes A² and around a series 50 of baffles A³ to a waste heating gas outlet A⁴;

this outlet, as shown, opening through the rear wall of the boiler housing adjacent the top of the latter. By means of an induced draft fan and stack (not shown) the heating gases are drawn down over the horizontal water tubes B' of the feed water heater B, which has a water inlet B² and water outlet B³. Situated directly below the economizer B is the air preheater C. The waste heating gases pass directly down between the horizontally extending tubes of the air preheater and then pass to the stack and atmosphere.

The air preheater C, constructed in accordance with the present invention, is situated in the lower part of the housing in which the economizer B is located. As seen in Figs. 1 and 2, the preheater is made up of four distinct banks of tubes C' through which air is passed and over which furnace gases pass, all of which tubes extend horizontally and transversely to the boiler housing. At the ends of the intertube space of the preheater are vertical tube sheets D' and D², in which the opposite ends of the tubes are secured. Between each tube sheet and the corresponding end wall of the preheater is a chamber space. Each space is divided centrally by a solid vertical partition E³. One of the portions of each chamber so divided is subdivided as shown in Fig. 1, by a partition E⁴ 55. The diagonally opposite chamber at the other end of the preheater is also subdivided by a partition E⁵. Thus by means of the partitions E³ and E⁴ the chamber space at the left end of the preheater is divided into three 60 subchambers E, E' and E² as shown in Fig. 1, the sub-chamber E comprising half of the chamber while the sub-chambers E' and E² comprise the other half of the chamber. The chamber at the other end of the preheater 65 is divided by the partitions E³ and E⁵ into three sub-chambers e, e' and e², the sub-chamber e being directly opposite to the sub-chambers E' and E², and the sub-chambers e' and e² directly opposite to the sub-chamber E at the opposite end of the preheater.

The preheater is thus designed to pass air through the preheater tubes in two distinct U-shaped streams, the legs of which are par-

allel but extend in opposite directions leaving the preheater at opposite ends by the conduits H and H' and going to opposite sides of the combustion chamber A'. To this end, in the construction shown in Figs. 1 and 2, the air going to the right side of the combustion chamber as seen from the front, enters the lower sub-chamber E², and by means of the partitions E³ and E⁴, is directed to the tubes C', through which it flows to the opposite end of the preheater to sub-chamber e rising vertically and returning through the tubes to the sub-chamber E' in the upper right side of the preheater as seen in Fig. 1. From this chamber the heated air is piped by the conduit H to the combustion chamber. The air to the far side of the combustion chamber enters the sub-chamber e² at the right side of the preheater as shown in Fig. 2, passes through the tubes C' to the sub-chamber E, rising and returning by way of the tubes to the sub-chamber e', and is piped to air inlets P in the far wall of the combustion chamber by the conduit H'. Air fans (not shown) are used to force the air to the preheater. Vertically and horizontally spaced along the rear wall of the preheater are small soot blower nozzles F arranged to be connected to an air or steam supply for periodically cleaning the accumulated soot and dust from the preheater tubes.

It will be observed that the preheater arrangement lends itself to effective counter-current operation. The incoming air absorbs heat from the heating gases passing around the banks of tubes, and still further absorbs heat while travelling through the upper banks of tubes.

In Figs. 3 and 4, a modified arrangement of the preheater is shown adapted for use with stoker fired boilers. The air is forced through the preheater tubes in two separate streams by the fans K' and K². The flow of air is seen to be the reverse of that shown in Figs. 1 and 2 as the streams enter by the upper banks of tubes M' and M² and leave the preheater by the lower banks of tubes M³ and M⁴. The counter-current effect is obtained by passing the heating gases from the combustion chamber by way of the passages N' and N² up through the preheater tube chamber. The induced draft fan K³ is used to assist the waste gas circulation. The partitions, tube sheets and end chambers are constructed as was shown in Figs. 1 and 2.

The preheater construction shown in the present application is especially adapted for boiler constructions wherein it is desirable to have equal supplies of hot air to inlets at both sides of the combustion chamber. It is obvious that the connections from the preheater outlets to the combustion chamber are shortened by the arrangement. There are special advantages in the present preheater construction over air preheater constructions

now in general use in which the air passing to opposite sides of the furnace is preheated in separate end to end banks of tubes. The tubes in such prior constructions are only about half as long as it is practically feasible and desirable to make the tubes in the use of the present invention. The reduction in the number of tubes required reduces the number of connections to the tube sheets, and results in a decrease in the cost of material and assembly. The use of tubes extending the full length of the preheater gives a compact arrangement accessible for inspection and repairs.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent is:—

1. In an air preheater, the combination with a housing and a plurality of side by side tubes within said housing, of means associated with the inter-tube space within the housing and with the space collectively formed by the tube passages for utilizing one of said spaces as a path of flow for heating gases, and dividing the other of said spaces into two similar paths of air flow, whereby the air to be preheated passes partly through one and partly through the other of said two similar paths of flow with the direction of air flow along one of said paths opposite to the direction of air flow along the other path.
2. In an air preheater, means for passing heating gases through said heater in a vertical direction, means for passing a current of air in a U-shaped path transversely to said flow of heating gases, and means for passing a second and separate current of air through said heater in a U-shaped path transversely to said flow of heating gases and in an opposite direction to said first mentioned current of air.
3. In an air preheater, a housing, a plurality of banks of air conduits alongside of each other in said housing and arranged to provide two separate paths of air flow in opposite directions, and means for passing heating gases vertically through said housing in a path normally to said paths of air flow and in contact with said conduits.
4. In an air preheater, the combination with a housing, of parallel tubes extending across said housing, means for passing heating gases vertically through the intertube

- space within the housing, and connections to the ends of the tubes providing two U-shaped paths of flow for the air to be pre-heated, each leg of each U-shaped path of air flow comprising a plurality of said tubes, the ends of one of said U-shaped paths of flow being at one end, and the ends of the other U-shaped path of flow being at the other end of the preheater.
- 5 5. An air preheater having a rectangular housing, vertical tube sheets adjacent to opposite ends of said housing and spaced therefrom to form end chambers therebetween, a plurality of parallel tubes extending horizontally in said housing and having their ends opening into said end chambers, a central vertical partition in each of said end chambers dividing the corresponding chamber into sections, a horizontal partition in 15 two diagonally opposite sections of said end chambers separating the upper and lower portions of the corresponding sections and forming two separate side by side U-shaped paths of flow through said tubes and end chambers terminating at opposite ends of 20 25 said preheater.

Signed at New York city, in the county of New York, and State of New York, this 29th day of July, A. D. 1926.
